HOMER P. LAMBERT, OF ANDERSON, INDIANA

ROTARY-DISK FILE

Application filed November 2, 1928. Serial No. 316,648.

This invention relates to rotary disk files particularly adapted to dressing down surfaces of wood, metal and the like, substantially as explained in my former application, Serial No. 265,720, filed March 29, 1928. In rotary files of this character which attain extremely high rotary speed, there is great danger of the centrifugal force, combined with the lateral pressure and the binding action, causing distortion which may interfere with the proper operation of the file or breakage which may injure the operator by parts being thrown.

Probably the most important object of the invention is to properly align the rotary disk file so that it will always run true in its rotary movement and will not be distorted because of misalignment thereof. This object is accomplished by securing the disk file peripherally and centrally to a rigid back plate or casing which reinforces and holds the same in true alignment.

Another object of the invention is to construct a rotary disk file so that the operator will be protected from any breakage or flying parts in the use of the device. To that end the disk file is peripherally surrounded and its rear surface enclosed by a rigid and relatively heavy back plate or casing. The rotary file is secured thereto both centrally and peripherally and rotates therewith so that the margin and the back of the disk file is wholly covered and protected.

Another object is the control of the dust discharge during the operation of the file. Without any such control, a stream of dust is discharged rearward against the operator and he must constantly work in that stream of dust. A dust chamber is provided in this invention between the rear of the rotary disk file and said reenforcing back plate or casing from which the dust escapes centrifugally through outlet openings in the periphery of the protecting plate or casing. Centrifugal force of the device causes centrifugal air movement through said outlet openings which carries with it the dust and discharges it out beyond the normal working position of the operator.

The full nature of the invention will be

understood from the accompanying drawings and the following description and claims:

In the drawings Fig. 1 is a side elevation of the apparatus showing it as applied to a piece of work, parts being broken away. Fig. 2 is a front elevation of the apparatus with some of the cutting teeth shown and the major portion thereof omitted. Fig. 3 is a central vertical section through the apparatus in condition for use. Fig. 4 is a similar section of the apparatus, while being assembled and prepared for use.

In the drawings there is shown a rotary disk file 10 being a hardened steel disk with a large number of burrs or cutting teeth 11 thereon and peripherally punched through the same and adapted to engage and dress down protruding surfaces of wood or other work 12 in order to smooth and properly dress the same. Said file is rotated at high speed by means of the drive shaft 13. The disk file 10 is provided with an annular and centrally positioned recess to cause the central portion 14 of the disk 10 to extend rearward and behind the operating plane of the disk file so that the binding nut 18 for holding it in place on the threaded portion 15 of the shaft 13 will not protrude forward into the plane of the burrs or cutting teeth 11, as shown.

The rotary disk 10 is provided with a rearwardly extending marginal edge 21 about its periphery which strengthens and slightly stiffens the file. The disk file is further strengthened materially by the flanged edge 21 being enveloped in a soft metal ring 22. The ring 22 is secured on a flange 21 by spot welding or other suitable means.

The entire disk file so far described is then secured on a relatively heavy thick back plate 25 of disk form and of substantially the same diameter as the disk 10 and having means for securing the margin and central portions to said back plate or disk 25. Thus, said back plate has on its side next to the file disk 10 a chamber 26 surrounding a central boss 27 which surrounds the threaded part 15 of the shaft 13, as shown.

Said back plate 25 also has a marginal rim 100

- 28 with a series of radially extending holes or apertures 29 through said marginal rim for the entire circumference of the device. Also said marginal rim 28 has an annular 5 groove at 30 in the front face thereof for seating the annular portion of the file disk 10 including its marginal flange 21 and reinforcing soft metal ring 22, as appears clearly in Figs. 3 and 4.
- 10 The above parts are assembled substantially as illustrated in Fig. 4 by the file disk 10 being seated on one side of the back plate 25 with the marginal rim of the former in the annular recess 30 in the rim 28 of the 15 latter, and with both members 10 and 25 mounted on the threaded portion 15 of the shaft 13. In that position the rearwardly extending portion 14 of the disk 10 is adjacent to but slightly spaced from the boss 27 20 on the rigid back plate 25. When the nut 18 is tightened down, it will spring the central part of the disk file 10 against the boss 28 of the back plate and bring the parts, when finally assembled for working, into the position shown in Fig. 3. Then the file disk will 25 be sprung into its working position so as to be securely held against the rigid back plate 25 and all parts of the disk file 10 be maintained in constant true alignment.
- 30 The foregoing device constructed as above explained renders the apparatus very rigid and strong and yet the file disk, which is made of hardened steel, has its usual characteristics, rendering it suitable for its work.
- 35 By reason of its sprung position in the center and the seating of its marginal ring 22 in the groove 30 of the back plate, its perfect alignment is assured and also the durability of its mounting.
- 40 The back plate 25 protects the rear side of the disk file from being engaged by workmen and also the marginal periphery thereof is protected by the rim of said back plate which is peripherally smooth. Likewise, said 45 back plate prevents any distortion of the disk file and any breakage thereof so that the workman will receive no injury from that cause. Furthermore, the workman will be protected from any rearwardly moving column of dust, as the dust which will enter 50 chamber 26 of the back plate and pass out centrifugally through the peripheral openings 29 beyond the working position of the workman.
- 55 The invention claimed is:
1. The combination with a rotary disk file having perforations in its face and a driving shaft on which it is centrally mounted, of a rigid back plate spaced from said disk file to form a dust chamber there-between and centrally mounted on said shaft with the margin of the disk file engaging the rim of the back plate, and means for clamping the central part of the disk file tightly against

the central part of the back plate, substantially as and for the purposes set forth.

2. A rotary file comprising a metal disk with a cutting surface on one side thereof, a rigid circular back plate, a driving shaft 70 centrally mounting said disk and said back plate with the margin of said disk in engagement with the rim of the back plate and the central part of the disk file normally spaced from the central part of said back plate when not clamped thereto, and means for clamping the central part of the disk file under tension against said back plate, substantially as set forth.

3. A rotary file comprising a metal disk 80 having a cutting surface on one side and a rearwardly extending marginal flange, a rigid circular back plate with a rim having an annular groove in its front face in which said marginal flange of the disk file is imbedded, a driving shaft extending centrally through both of said members with a shoulder behind and adjacent to the back face of said back plate and the forward end of said shaft threaded, and means on the shaft for 85 clamping the central part of the disk file against the central part of said back plate, substantially as set forth.

4. A rotary file comprising a metal disk having a cutting surface on one side and a 95 rearwardly extending marginal flange, a rigid circular back plate with a rim having an annular groove in its front face in which said marginal flange of the disk file is imbedded, a driving shaft extending centrally 100 through both of said members with a shoulder behind and adjacent to the back face of said back plate and the forward end of said shaft threaded, the central part of said disk file being spaced away from the central part 105 of said back plate when not under tension, and a nut on the front end of the shaft for clamping the central part of said disk file under tension against the central part of the back plate, substantially as set forth.

5. A rotary file comprising a metal disk with a cutting surface on one side thereof, a rigid circular back plate, a driving shaft on which said two members are centrally mounted with said disk held against the back plate, 115 said back plate being recessed in its front face to form a dust chamber behind the metal disk and with dust outlet openings in the rim of the back plate, substantially as set forth.

6. A rotary file comprising a metal disk with a cutting surface on one side thereof and having a rearwardly inset central portion and an inwardly extending marginal flange on the periphery thereof, a rigid circular back plate with a central forwardly extending boss and a forwardly extending rim with an annular groove in the front face of the rim, which receives the rearwardly extending marginal flange of the disk file, and said back plate be- 125 130

ing recessed to form a dust chamber in the front face thereof behind said disk file and with dust outlet openings in the rim of said back plate, a driving shaft with a threaded portion extending centrally through said disk file and said back plate and a shoulder against the rear face of the back plate, and a nut on the forward end of the shaft clamping said disk against said back plate, substantially as set forth.

10 In witness whereof, I have hereunto affixed my signature.
